CLAIM

The ornamental design for a decorative fireplace set as shown and described.

DESCRIPTION

1. Decorative fireplace set
  2. Decorative fake log
- FIG. 1.1 is a front perspective view of the article;
FIG. 1.2 is a front elevation view thereof;
FIG. 1.3 is a rear elevation view thereof;
FIG. 1.4 is a left-side view thereof;
FIG. 1.5 is a right-side view thereof;
FIG. 1.6 is a top plan view thereof;
FIG. 1.7 is a bottom plan view thereof;
FIG. 1.8 is a cross-sectional view thereof, taken along lines 1.8-1.8 of Fig. 1.4;
FIG. 1.9 is a cross-sectional view thereof, taken along lines 1.9-1.9 of Fig. 1.4;
FIG. 1.10 is a cross-sectional view thereof, taken along lines 1.10-1.10 of Fig. 1.2;
FIG. 1.11 is a cross-sectional view thereof, taken along lines 1.11-1.11 of Fig. 1.2; and
FIG. 1.12 is a cross-sectional view thereof, taken along lines 1.12-1.12 of Fig. 1.2.

(Continued)

The design is the visual features of the decorative fireplace set as shown in the accompanying drawings. The broken lines in the drawings do not form part of the design.
